(57) **CLAIM**

The ornamental design for a wearable light, as shown and described.

DESCRIPTION

FIG. 1 is a front, right and top perspective view of a wearable light, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1 comprising a front side of a buckle.

FIG. 10 is a partial enlarged view of an area labeled 10 in FIG. 1 comprising a part of a belt.

FIG. 11 is a partial enlarged view of an area labeled 11 in FIG. 2 comprising a fastener.

FIG. 12 is a partial enlarged view of an area labeled 12 in FIG. 2 comprising a rear side of a buckle.

FIG. 13 is a partial enlarged view of an area labeled 13 in FIG. 3.

FIG. 14 is a partial enlarged view of an area labeled 14 in FIG. 4.

FIG. 15 is a partial enlarged view of an area labeled 15 in FIG. 5.

FIG. 16 is a partial enlarged view of an area labeled 16 in FIG. 6.

FIG. 17 is a partial enlarged view of an area labeled 17 in FIG. 7; and,

FIG. 18 is a partial enlarged view of an area labeled 18 in FIG. 8.

The dash-dash broken lines in the drawings are for the purpose of illustrating portions of the article that form no part of the claimed design. The dot-dash broken lines in the

(Continued)

drawings are for the purpose of illustrating boundaries of the portions shown enlarged in the views, and form no part of the claimed design.
